UNITED STATES PATENT OFFICE.

HUGO DUDECK, OF RISEDORF, GERMANY.

STAMPING-PRESS.

SPECIFICATION forming part of Letters Patent No. 661,794, dated November 13, 1900.

Application filed May 2, 1898. Serial No. 679,539. (No model.)

To all whom it may concern:

Be it known that I, HUGO DUDECK, machine manufacturer, a citizen of the German Empire, residing at Risedorf, near Berlin, have invented certain new and useful Improvements 5 in Draft-Presses; and I do hereby declare the following to be a full, clear, and exact description of the invention, such as will enable others skilled in the art to which it appertains to 10 make and use the same.

The present invention relates to draft-presses and stamping-machines, its object being to provide a machine of this nature the working parts of which are uniformly adjustable and wherein the stroke of the cams acting on the pressing-rollers is not directly transmitted to the combined plunger-guide and movable work-holder.

It consists in the novel arrangement and 20 combination of parts to be presently described, and definitely set forth in the claims hereto appended.

In the accompanying drawings, Figure 1 is a side elevation, partly in section, of a mechanism embodying my improvements; and 25 Figs. 2 and 3 show, respectively, end and plan views thereof.

Referring to the drawings, in which like letters of reference denote like parts, *a* designates a combined plunger-guide and movable work-holder, and *d* a pressure-plate inserted in the top thereof. A ring *b* is revolvably mounted in the plate *d* and provided with any common form of screw-thread meshing with corresponding thread in the guide *a*. The combined plunger-guide and movable work-holder can be adjusted in respect to its lowermost position by simply introducing a key of special form through the adjusting 35 holes *c* to turn the ring, whereby the guide can be raised or lowered, as desired. Clamp-screws *e e* are provided to maintain the adjustment between ring *b* and work-holder *a* in fixed relation to each other when satisfactorily adjusted. To prevent said guide from 40 sustaining any blow or impact, the following mechanism has been devised: Link-rods *h h* are movably connected to the pressure-plate *d* and carry each a pressure-roller *g*, Fig. 1.

50 The pressure-rollers *g* are actuated by cams *f*, which are rigidly mounted on the drive-shaft, the links *h* being guided in their reciprocations by levers *i*, carried by an oscillatory shaft *k*, journaled in the framework. A simi-

lar lever *l*, mounted upon this shaft, carries 55 a roller at its upper end, adapted to be raised to elevate the work-holder and release the articles being worked upon by means of a cam *m*. The cams *f* act only on the rollers *g* to turn the levers *i* and push downward the 60 link-rods *h*, while the cams *m* act to turn the levers *l* and thereby through their rigid connection with rock-shaft *k* and levers *i* to raise the link-rods *h*. The rock-shaft and levers *i* act to guide the upper end of the links *h* in 65 an exact path approximately in line with the motion of the work-holder *a*. An uncertain or inexact movement of the combined plunger-guide and movable work-holder is thus absolutely excluded. The latter being periodically and properly raised and lowered by the 70 rods *h* is timed to press down upon and hold the plate or other work in the press in advance of the movement of the main or central plunger and subsequently to release the 75 work.

Having thus described my invention, I claim—

1. In an apparatus such as described, the combination of a pressure-plate, a ring revolvably mounted therein, a combined plunger-guide and movable work-holder carried thereby, and means substantially as described for actuating said parts, as and for the purpose set forth. 85

2. The combination in a draft-press, of an adjustable combined plunger-guide and movable work-holder, a pressure-plate above the holder, a ring revolvably mounted in said plate, means for adjusting the position of said holder 90 in relation to said ring and means substantially as described for actuating said parts as and for the purpose set forth. 85

3. The combination in a draft-press, of an adjustable combined plunger-guide and movable work-holder, a pressure-plate above the holder, a ring revolvably mounted in said plate and screw-threaded to said holder, pressure-rollers movably connected with the pressure-plate and cam mechanism for actuating said 100 parts, substantially as described. 95

In testimony whereof I affix my signature in presence of two witnesses.

HUGO DUDECK.
